(57) **CLAIM**

The ornamental design for a motorcycle foot peg, as shown and described.

DESCRIPTION

FIG. 1 is a perspective view of a motorcycle foot peg showing my new design;

FIG. 2 is a top plan view thereof; and,

FIG. 3 is a front elevational view thereof, the rear elevational view being a mirror image thereof.

The broken line showing of the mounting portion of the motorcycle is for illustrative purposes only and form no part of the claimed invention.
